UNITED STATES PATENT OFFICE.

JOHN MAXWELL COOTE, OF ELIZABETH, NEW JERSEY.

RENEWABLE CARTRIDGE-FUSE.

1,284,247.

Specification of Letters Patent. Patented Nov. 12, 1918.

Application filed April 13, 1917. Serial No. 161,753.

To all whom it may concern:

Be it known that I, JOHN MAXWELL COOTE, a citizen of the United States, and a resident of Elizabeth, in the county of Union and State of New Jersey, have invented certain new and useful Improvements in Renewable Cartridge-Fuses, of which the following is a specification.

The invention relates to improvements in electrical fuses, more particularly of the cartridge ferrule type, wherein a fusible wire or link is held in a tubular insulating member between two cap or contact members.

The present invention has for its object to provide a fuse of this character wherein the said fusible element may be inexpensively and readily replaced in case the same is blown by excessive current, and wherein the ferrule portion is extremely simple, being composed of but two parts. It has for a further object to insure, without the use of chucks or the like, a positive and substantial full sectional contact between the said fusible element and the contact caps; and to so locate the former with respect to the latter that it will not be twisted off or cut off at the contacting portion.

In the accompanying drawings, which illustrate the invention—

Figure 1 is a front elevation of the improved fuse, partly in section.

Fig. 2 is an end view thereof.

Fig. 3 is a longitudinal section.

Figs. 4 and 5 illustrate a modification, Fig. 4 being an end view, and Fig. 5 a sectional view of the modified cap.

Fig. 6 is a longitudinal section of a further modification.

Similar characters of reference designate corresponding parts throughout the several views.

Referring to the drawings, 10 designates the fuse carrier or cartridge, usually tubular in form and of suitable insulating material, the same being exteriorly threaded at each end to receive metal or conducting terminal caps or ferrules 11 and 12 respectively. The fusible element, which may consist of a wire 13 of the rated capacity, as shown in Figs. 1 to 3, or of a link 14, Figs. 4 to 6, is adapted to be retained by the said caps, in manner hereinafter set forth, within the cartridge 10; and may be surrounded in the former embodiment by a non-fusible gas absorbing filling material as sand, plaster of Paris, chalk, asbestos or the like, as is

well understood. It may be found desirable, also, to concentrate at the inner ends loose threaded fiber or asbestos.

In order to properly secure the fusible element to the respective caps, reference being had more particularly to the embodiments shown in Figs. 1 to 3 wherein a fusible wire is employed, each of the said caps is provided with a diametral slot or kerf 15, extending from the top to the interior of the cap, and the width of same being made just sufficient to admit a wire of the largest diameter for the rated capacity of the fuse as determined by the character of said fuse. 60 The fusible wire is designed to be located substantially centrally in the cartridge, and the caps may be conveniently turned about same as an axis to fix them upon the respective ends of the cartridge. One end of the 70 fuse wire is first firmly secured in position by providing an eye 16 thereon and locking the same to the cap 11 by means of a screw 17. An opening 18 is drilled for this purpose through the upper portion of the cap at 75 right angles to the kerf 15 and provided with a tapped inner portion beyond said kerf to lock the screw; and also to securely draw the two separated portions of the cap together with the eye 16 between same. 85 thereby insuring a positive and ample full sectional contact. After the one end has thus been firmly located, the cartridge is screwed into position on said cap 11 and filled, if desired, and cap 12 screwed on, the 90 turning of same being without effect on the wire. The other end of said wire is then turned over a screw 19 and the latter turned to firmly mount said end in the cap 12.

When employing a link fusible element 14, 95 for example of the notched character shown in Fig. 6, the ends of this link are provided with suitable perforations 20 through which the screws of the cap may pass; but it must be borne in mind that provision must then be 100 made whereby a cap can be freely screwed on to the cartridge without rotating the said link relatively thereto. For this purpose, in the embodiment disclosed in Figs. 4 and 5, a plurality of chuck members or pieces 21, 105 are mounted in a central opening 22 of one of the caps as the cap 23, which is also provided with a kerf 24 as in the previous instance. In screwing down said cap, the fusible element 14, which is held between the 110 chuck pieces, will not be affected by the turning of the said cap, which moves freely

about the said chuck members 21. A screw 25, however, is provided to pass through an opening 26 drilled into the cap and through the chuck members, the inner end of said opening beyond the kerf being tapped to lock the screw. In locking the screw, the said chuck members will be drawn up tightly to secure the one end of the fusible link 14 and insure proper contact.

10 Or, as disclosed in Fig. 6, caps 30 and 31, similar to those shown in Figs. 1 to 3, may be employed, provided the threads of same and of the corresponding ends of the tubular member 32 are arranged to run in opposite directions, thus enabling the said caps to be drawn toward each other on said tube by rotating the latter and holding the former against rotation. The position of the link 14 relatively to the caps 30 and 31 is 15 thereby not disturbed; and to secure same to the caps for proper contact, it is necessary merely to tighten corresponding screws 33 and 34 as in the previously described, embodiments. The screws pass through 20 corresponding perforations 35 and 36 of the link, and one of which, as the perforation 36, is in the nature of a slot.

The fuse hereinbefore described is so constructed that it is extremely efficient in operation, readily disassembled for a substitution of a new fuse element, and is as readily assembled, requiring no particular skill or special tools in either case. Furthermore, there are no projecting parts of 35 the fuse, but the same presents a smooth and finished appearance and the length of same over all remains always the same. A minimum of parts are employed and the contacts are made to the caps or ferrules 40 independently of the tube portion, thus obviating the possibility of loosening contacts by difference in expansion and contraction due to temperature variations. There is, furthermore, a large section of metal for 45 heat dissipation and ample opening for gas ventilation.

I claim:

1. An electrical fuse cartridge, comprising: a tubular casing of insulating material, and a fuse element therein; cap members at each end thereof, at least one of said members being provided with a longitudinal kerf within which is located one 50 end of the fuse element; and means passing through said kerf to hold said fuse element end therein and to insure positive contact between the same and the sides of said kerf by drawing the separated portions of the cap together.

60 2. An electrical fuse cartridge, comprising: a tubular casing of insulating material, having oppositely threaded ends, and a fuse element in said casing; cap members fitting over each end of said casing and 65 rotatable thereon, at least one of said cap

members being provided with a longitudinal kerf adapted to receive an end of the fuse element; and means to hold said fuse element therein and to insure positive contact between the same and the sides of the 70 kerf.

3. An electrical fuse cartridge, comprising: a tubular casing of insulating material, and a fuse element therein; cap members at each end thereof, one of said cap 75 members being provided with a longitudinal diametral kerf within which is located one end of the fuse element; and a screw passing through said cap at right angles to said kerf to hold the fusible element end therein 80 and to draw the separated portions of the cap together to insure a positive contact between the said element and the said cap.

4. An electrical fuse cartridge, comprising: a tubular casing of insulating material, and a fuse element therein; cap members at each end thereof, one of said cap 85 members being provided with a longitudinal diametral kerf adapted to receive an end of the fuse element; and a screw passing 90 through said cap at right angles to said kerf and through said fusible element to hold the fusible element therein and to draw the separated portions of the cap together to insure a positive contact between 95 the said element and the said cap.

5. An electrical fuse cartridge, comprising: a tubular casing of insulating material; cap members at each end thereof, one of said cap members being provided with a 100 longitudinal diametral kerf adapted to receive an end of the fuse element and of width determining the character of the fuse element employed; a screw passing through said cap at right angles to said kerf to hold the fusible element therein and to draw the separated portions of the cap together to insure a positive contact between the said element and the said cap; and a fusible link provided with perforations at each end 105 adapted to receive the said screw to be locked thereby to said cap, and to make positive contact with said caps when the screw is drawn tight.

6. An electrical fuse cartridge, comprising: a tubular casing of insulating material, having oppositely threaded ends; cap members adapted to be screwed thereon and provided with a longitudinal kerf; and a fusible link fitting the kerf of said caps 115 which are adapted to be screwed upon the tubular casing ends about the projecting link ends; and means passing through said link and into said caps to secure the former to the latter and insure positive contact 120 between same.

7. An electrical fuse cartridge, comprising: a tubular casing of insulating material, having oppositely threaded ends; cap members adapted to be screwed thereon and 125

provided with a longitudinal kerf; a fusible link provided with a perforation at one end and a longitudinal slot at the other; and screws passing into said caps transversely through the kerf thereof and respectively through the perforation and longitudinal slot of the fusible link to secure the

latter to the caps and insure positive contact therewith.

Signed at New York, in the county of 10
New York and State of New York, this 4th
day of April, A. D. 1917.

J. MAXWELL COOTE.
